UNITED STATES PATENT OFFICE

2,362,536

APPARATUS FOR CONDITIONING THE SURFACES OF METAL BODIES

James H. Bucknam, Cranford, N. J., assignor to
The Linde Air Products Company, a corpora-
tion of Ohio

Original application May 11, 1940, Serial No.
334,510. Divided and this application June 30,
1942, Serial No. 449,986

14 Claims. (Cl. 158—27.4)

This invention relates to blowpipe apparatus for thermally conditioning the surfaces of ferrous metal bodies and more particularly to blowpipe apparatus for thermochemically removing a relatively shallow layer of surface metal from a steel body such as a billet, bloom, slab, or the like.

This application is a division of the copending United States patent application Serial No. 334,510 filed May 11, 1940, jointly by Arthur M. Keller, James H. Bucknam, and Alfred J. Miller, now Patent No. 2,312,418.

In the casting of steel ingots and during the hot rolling of steel, defects such as scale, cracks, seams, slag-inclusions and the like form on and in the surfaces of the steel bodies and cause imperfections in the finished rolled products unless removed. In order to reduce the number of rejections of finished rolled products, the surface defects are generally removed before or during an intermediate stage of the rolling. Scale is commonly removed by pickling and other defects have often been removed by mechanically cutting or chipping away the defective surface metal. Hand-operated blowpipes, commonly referred to as hand-deseaming blowpipes, are now also used for thermochemically removing the defective surface metal adjacent each defect by effecting the combustion of the steel with oxygen. Recently, machines employing suitable blowpipe means have come into use for thermochemically conditioning the surface of billets, and the like. These machines may be used for conditioning steel shapes, either when cold or while they are at a rolling temperature and are passing from one roll stand to another such as is commonly employed in a steel mill.

The present invention provides blowpipe or torch means for thermally conditioning or scarfing the surface of a steel body such as a bloom or slab or for eliminating scale, and more particularly blowpipe means suitable for use in a machine for thermochemically removing a layer of surface metal from the body, preferably while the steel body is at an elevated temperature. A multiple nozzle head discharging high-temperature preheating flames and a composite, substantially sheet-like oxygen stream is moved relatively along the slab and is maintained in contact with the work surface during such movement in order that a substantially uniform depth of metal may be removed and the gas efficiently used.

Accordingly, the principal objects of this invention are to provide improved apparatus for surface conditioning a metal body; to provide such apparatus for maintaining a blowpipe head

in uniform contact with the steel body irrespec-
tive of any warp or twist of the surface of the
body; to provide such apparatus which includes
an improved, water-cooled shoe for contacting
the surface of the steel body to maintain the
blowpipe nozzle orifices in operative relation to
the surface and for protecting the blowpipe noz-
zles; to provide such apparatus which includes
an improved nozzle block; and to provide an im-
proved blowpipe assembly which can be used in
any position for conditioning either hot or cold
bodies.

These and other objects and novel features of
this invention will become apparent from the fol-
lowing description taken in connection with the
accompanying drawings, in which:

Fig. 1 is a side elevational view of an exem-
plary blowpipe apparatus embodying the features
of the present invention;

Fig. 2 is an elevational view of the rear of the
blowpipe apparatus of Fig. 1;

Fig. 3 is an enlarged fragmentary detail view
of the front of the blowpipe head of Fig. 1;

Fig. 4 is a view on an enlarged scale of a sec-
tion through the blowpipe head taken along line
4—4 of Fig. 3;

Fig. 5 is a fragmentary view similar to Fig. 4
taken along line 5—5 of Fig. 3;

Fig. 6 is a fragmentary view of a section dis-
closing the means for sealing the passage for the
end nozzles of each head which section is taken
along line 6—6 of Fig. 3;

Fig. 7 is a fragmentary view of a section
through the nozzle block disclosing the preheat-
ing gas distributing passages and taken along
line 7—7 of Fig. 4;

Fig. 8 is a sectional view through the nozzle
block to show the cutting oxygen distributing
chambers and taken along line 8—8 of Fig. 4;

Fig. 9 is a view of a fragmentary section
through the nozzle block taken along line 9—9
of Fig. 5;

Fig. 10 is a view of a fragmentary section
through the nozzle block taken along line 10—10
of Fig. 5;

Fig. 11 is a rear elevational view of the nozzle
shoe; and

Fig. 12 is a front elevational view of the nozzle
block with the nozzle shoe removed.

The conditioning head may be supported in an
operative position adjacent the body to be condi-
tioned by any suitable mechanism. Especially
when the conditioning head is adapted for de-
surfacing a ferrous metal body, it may be sup-
ported adjacent the body by a desurfacing ma-

chine such as is shown and described in the aforementioned United States Patent 2,312,418, of which this is a divisional application. The desurfacing machine preferably includes means for moving the desurfacing head in a direction toward and away from the body prior to and after a surface removing operation, and means for propelling the body longitudinally while the head is held in contact with a surface of the body during the surface removing operation. Obviously if desired the body may be stationary and the head may be propelled along the body. In either arrangement, there is provided relative movement between the body and head and in such a direction as to remove successive portions of surface metal from the body.

As shown by the drawings, the composite desurfacing head comprises a plurality of similar blowpipe heads H which are supported on a carrier plate 20 and are preferably urged into contact with the body at a predetermined pressure. The heads H are shown as being urged against the bottom surface of a slab S which is supported and propelled in the direction of its length. The number of heads employed depends upon the width of surface to be conditioned.

The blowpipe heads H are similar and only one will be described in detail. Each head H comprises a nozzle retaining member or block 21 and a removable nozzle protecting shoe portion 22. The head H is removably attached to the carrier plate 20 by bolts 23 and 24. An elongated strip or perforated clamping bar 26 may be placed between the heads of bolts 23 and the head H as shown and, if only part of the bolts 23 should be tight, the head H will still be retained securely in place. In the block 21, there are a plurality of similar oxidizing gas passages 27 (Figs. 4 and 7) each of which terminates in an enlarged and partly threaded recess at its forward outlet end to operatively receive the inlet end of a nozzle 28 removably secured therein by means of an externally threaded nozzle retaining nut 29. The inlet end of the passage 27 communicates with a chamber 30 formed in block 21, there being a chamber 30 for each two passages 27 (Fig. 8). The inlet end of each chamber 30 is adapted for receiving the threaded end or connection of an oxidizing gas supply tube 31 which in turn communicates with a source of oxidizing gas. The oxidizing gas flows from each supply tube 31, through distributing chambers 30, the two oxidizing gas passages 27 and through the central oxidizing gas bores of a corresponding pair of nozzles 28 secured in block 21. A sufficient number of tubes 31, passages 27 and chambers 30 are provided in each block 21 so that the oxidizing gas orifices 28 of all of the nozzles in each head are supplied with oxidizing gas such as oxygen. Each tube 31 contains a manually operable valve 32 for controlling the flow of oxidizing gas to the corresponding pair of nozzles 28.

The outlet end of each passage 27 is formed to provide a pair of seats which coat with seating surfaces on the inlet end of a nozzle 28 to form gas-tight seals at 33 and 34, (see Fig. 6). Between these seating surfaces, the cavity in the block 21 is formed larger than the nozzle to provide the usual combustible or preheat gas distributing chamber at 35 for distributing a combustible gas mixture, such as oxygen and acetylene to the preheat passages in the nozzle. Such preheat passages terminate in preheat orifices 28" shown in Fig. 3, for producing heating flames adjacent the oxygen stream. As disclosed in Fig.

7, a plurality of passages 36 may be drilled in the block 21 each communicating with one of the chambers 34. The passages 36 are so drilled that the inlet ends of each pair of passages intersect at the outlet end of a passage 37. The outer ends of passages 36 may be plugged with silver solder or other suitable means. The inlet end of each passage 37 is adapted to receive the threaded end of a blowpipe tube 38 of a blowpipe or gas-mixing device 39. A combustible gas and preheating oxygen is mixed in the blowpipe 39 and flows through tube 38, passage 37, two passages 36, into two chambers 35 and from each chamber 35 to the preheating passages and orifices 28" of the corresponding nozzle 28. For each pair of nozzles 28, there is provided a separate blowpipe 39, a passage 37 and two passages 36.

The shoe 22 is attached to the nozzle block 21 by bolts 40 and 41 as more clearly shown in Figs. 4 and 5. The bolts 40 extend through the shoe 22 and threadedly engage block 21. Bolts 41 are inserted from the rear of block 21, extending through a cooling chamber formed in the block 21, to threadedly engage the shoe 22. To prevent leakage of cooling fluid from the chamber 43 along bolts 41, a sealing or packing sleeve 44 is provided for each bolt 41. A gasket 45 may be provided between shoe 22 and block 21 to prevent leakage of cooling fluid therebetween. The forward end of each nozzle 28 extends through a hole 46 in the front wall of the shoe 22 and the forward end of the nozzle is substantially flush with the outer wall of the shoe. To prevent cooling fluid from leaking past the nozzle 28 to the outside of the shoe, a packing ring 47 which encircles the central portion of the nozzle is pressed against the inner front wall surface of shoe 22 by a compressed spring 48 surrounding the nozzle. Each nozzle is retained in the head H by similar means, but because of lack of sufficient space, the end nozzles in each head are provided with slightly different packing arrangement as shown in Fig. 6. The end holes 46 are enlarged at approximately the central portion and contain a packing ring 49. The packing rings 49 fit the outer walls of the end nozzles tightly enough to prevent leakage of fluid along the nozzles. If there is enough space, the end nozzles could be packed in the same manner as the other nozzles.

With this construction of the blowpipe head, the nozzles of each head H may be readily removed, all or singly, for replacement or inspection. By removing bolts 40 and 41, the shoe 22 may be readily removed to expose the nozzles, which are individually removable for replacement, repair, or inspection. Therefore, the head may be readily dismantled, repaired and assembled. By loosening bolts 23 and 24, the head H may be readily removed as a unit for repair or replacement.

The heads H are in contact with the bottom surface of a usually hot slab and are in a zone of high-temperature heat from the slab, the preheating flames, the heat of the reaction and the hot slag. The heads and nozzles must be adequately cooled to prevent overheating. Each nozzle block 21 is adapted to receive a water inlet connection 50, and has formed therein two transverse chambers 51 and 53 and has also formed therein a forward cavity 52 which coats with a cavity 53 in the shoe 22 to form the relatively large cooling chamber 54. A passage 55 connects the inlet 50 and chamber 51. A passage 56 provides communication between chambers 51 and 54 and passage 57 provides communication be-

tween chambers 54 and 43. The nozzle block contains ribs 58 (Fig. 12) formed in the cavity 52 that engage similar ribs 60 (Fig. 11) formed in cavity 53 of the nozzle shoe. The ribs 58 and 60 strengthen the parts and aid in correctly positioning the block and shoe when they are being fastened together. Passages 56 are formed in ribs 58 so that cooling fluid can readily flow to all portions of the chamber 54.

In the block 21 there is a bore 62 (Fig. 5) adapted to receive the threaded connection 63 having attached thereto a length of overflow tubing 64 which extends from connection 63 through bore 62 to substantially the top of chamber 43. Cooling liquid, such as water, flows from a supply tube 65, which is connected to a suitable source of supply, through connection 66, passage 55, chamber 51, passage 56, chamber 54, passage 57, into chamber 43 and out the overflow tube 64 and through connection 68 and a tube 66 to a drain. The cooling fluid chambers and connecting passages are so arranged that all portions of the head and nozzles are adequately cooled. The central portions of nozzles 28 are completely surrounded by cooling fluid and the gas passages 31 are well cooled to prevent overheating and possible preignition of the combustible gas mixture. The forward or front faces only of the nozzles 28 are exposed to the heat but otherwise are fully enclosed. By having the inlet end of overflow tube 64 positioned at the top of chamber 43, the chambers of the head are maintained full of cooling fluid even when desurfacing the bottom surface of a slab.

There may be any convenient number of nozzles in a head but as herein shown and described, each head H comprises a nozzle header or block 21, a shoe 22, eight nozzles 28, four blowpipes or mixers 39 for supplying mixed combustible gas, four oxygen supply lines 31, a fully enclosed cooling system, and the necessary valves for controlling the flow of the gases and cooling fluid. The nozzles in each blowpipe head are so spaced that the sides of the individual scarfing oxygen streams from the nozzles merge so as to direct a substantially sheet-like stream of oxygen onto the surface of slab S. The bearing surface of shoe 22 which contacts the slab is subject to damage by abrasion, and to protect the shoe, ridges of a metal which is resistant to abrasion at high temperatures may be deposited, as at 67, on the slab contacting surface of the shoe 22. Each head has at least two ridges 67 which extend forwardly and rearwardly and form supporting bearings for engagement with the work surface. The ridges 67 are spaced along the head and provide channels between them that permit passage of gas between the head and the work surface. To increase additionally the useful life of the head, a layer of abrasion-resistant material may be deposited on the shoe 22 and block 21 as is shown generally at 68 and 69, respectively. As shown in Fig. 3, the layer 68 covers substantially completely the front face of the shoe 22 through which the nozzles 28 pass except the openings 48 for the nozzles. A renewable layer of protective material for the front face is thus provided. As shown in Figs. 4 and 5, the shoe 22 overlaps the forward corner of the block 21, as indicated at 10, so that any force or shock on shoe 22 is taken by the block 21 and shoe 22 can not shift and damage the nozzles or break or strain the bolts 40 or 41.

There is an oxygen supply line 71 for each head H (Figs. 1 and 2). Each oxygen line 71 is con-

nected to a suitable source of supply and to an oxygen header 72 from which lead four lengths of tubing 73, each of which is connected to one of the four tubes 31. For each head H there is a length of tubing 75 which is connected through a suitable length of pipe and hose connection to an acetylene header 76 and is also connected to a suitable supply source of acetylene. Four lengths of copper tubing 77 are connected to acetylene header 76 and each length of tubing contains a manually operable valve 78 and is connected to one of the four blowpipes 39. Similarly, the preheat oxygen supply line 79 communicates with a suitable supply source, not shown, and is connected to a preheat oxygen header 80. Each of four lengths of copper tubing 81 communicate through a manually operable valve 82 with the header 80 and with one of the blowpipes 39 to supply preheat oxygen thereto.

20 A length of copper tubing 83 is connected to a source of constant temperature cooling liquid such as water and to one of the blowpipes 39. The blowpipes 39 are connected by short lengths of tubing 84 and cooling water flows from one blowpipe to the next through tubes 84. Cooling water flows from the last blowpipe in each head through a length of tubing 85 to a drain, not shown. The water for cooling the blowpipes is preferably heated to a low constant temperature 30 so as not to vary with the weather or temperature of the supply main.

By means of the manually operable valves in the preheating acetylene and oxygen lines and in the cutting oxygen line, the nozzles may be shut off in pairs, if for any reason it is desired to reduce the total effective width of the desurfacing flame produced by the heads H. Thus, when conditioning the surface of a metal body which is narrower than the width of the heads, the end nozzles may be shut off in pairs by means of valves 82, 78, and 32 so the effective width of the heads is substantially equal to the width of the surface. Normally, all manually operable valves for the nozzles needed to cover the desired width of surface are open and the flow of gases is controlled by electrically operable stop valves and a switch-means for controlling all such electrically operable stop valves not shown may be conveniently located at a single point.

50 Obviously, certain features of this invention may be used independently of others and changes may be made in various parts of the apparatus without departing from the spirit and scope of the invention. For example, although as herein disclosed, the apparatus is especially adapted for desurfacing semi-finished relatively wide steel slabs while they are at a red heat and in transit between successive rolling operations, it will be understood that the same principles are applicable to the desurfacing of relatively narrow steel billets, blooms, and the like which are cold or at ordinary atmospheric temperature. In addition, this surface conditioning apparatus could be used for directing gases, such as heating flames onto the surface of a body for thermally removing scale therefrom. Furthermore, the blowpipe heads could be used for desurfacing surfaces of steel bodies in other positions. For instance, these heads are suitable for desurfacing the top or side surfaces of either hot or cold steel bodies.

70 I claim:

1. A nozzle holding and protecting device comprising a nozzle block adapted to be secured to a support and operatively receive a row of nozzles; and a shoe removably attached solely to

said block and adapted substantially to enclose said nozzles except the orifice ends thereof, said shoe and said block being constructed and arranged to form a fully enclosed cooling liquid chamber therebetween through which said nozzles extend and constructed and arranged so that said shoe is removable from said block to expose said nozzles.

2. A desurfacing head comprising a nozzle block adapted to be secured to a support and operatively receive a row of nozzles; a shoe removably attached solely to said block and adapted substantially to enclose said nozzles except the outlet orifice ends thereof, said shoe and said block being constructed and arranged to form a substantially fully enclosed cooling liquid chamber therebetween through which said nozzles extend and so that said shoe is removable from said block to expose said nozzles; and a deposit of wear-resistant metal on said shoe for engaging the workpiece and positioning said nozzles in a predetermined operative relation to the surface of said workpiece.

3. Blowpipe apparatus comprising a block, said block having therein a series of openings each adapted operatively to receive a nozzle, gas passages for separately conveying a heating gas and an oxidizing gas to each of said openings, and a substantially fully enclosed cooling liquid chamber; a row of nozzles secured in said openings; a nozzle shoe removably attached solely to said block and substantially completely enclosing all of said nozzles except the orifice ends thereof, said block and said shoe being constructed and arranged to form a fully enclosed cooling liquid chamber therebetween; and means for removably securing said block to a surface conditioning apparatus.

4. Blowpipe apparatus comprising a nozzle block adapted operatively to receive a nozzle in each of a series of openings formed in a flat forward face of said nozzle block and adapted to be removably attached to a supporting means; and a nozzle protecting shoe secured fluid-tightly against said forward face and having a front face through which said nozzles extend and a work-engaging portion disposed on one side of said nozzles and obliquely thereto, said work engaging portion overlapping the forward corner of said block on said side of the nozzles, said shoe being secured to the block by screws entering from the front of the shoe into said block on the side of the nozzles opposite said work-engaging portion and by screws extending from the rear of the block into said overlapping portion.

5. Blowpipe apparatus comprising a nozzle block adapted operatively to receive a nozzle in each of a series of openings formed in a flat forward face of said nozzle block and adapted to be removably attached to a supporting means; and a nozzle protecting shoe removably secured solely to said block and fluid-tightly against said forward face, said shoe having a work-engaging wall with a surface portion adapted to slidably engage the surface of a workpiece, a portion of said wall overlapping a corner portion of said block, said shoe and said block being so constructed and arranged that a force against said shoe is taken by said block and transmitted therethrough to said supporting means without tending to shift said nozzles.

6. Desurfacing apparatus for thermochemically removing a layer of surface metal from a ferrous metal body comprising a head having a front face; a row of uniformly spaced apart passages opening through said front face and adapt-

ed to discharge initially parallel jets of desurfacing oxygen against a work surface at an acute angle; passage means in said head for supplying oxygen to the inlet ends of said oxygen passages; interconnected passages formed in said head for conveying cooling fluid therethrough; a wear-resistant surface portion on a side of said head adjacent said front face for engaging said work surface; and a renewable layer of protective material covering said front face substantially completely except where said passages open therethrough.

7. A torch comprising an elongated head having a face in which are a number of orifices at spaced points lengthwise of said face and from which desurfacing jets of oxygen are directed against a workpiece, a supporting shoe on said head, said shoe having a surface portion for supporting the torch on the workpiece, the width of said shoe being substantially as great as the length of said head, and the length of said shoe being at least one-half as great as the width, and having said surface portion so disposed with respect to said face that the jet orifices are at a predetermined spacing from, and inclination to, the surface to be scarfed when the supporting shoe is in surface contact with the workpiece.

8. A scarffing torch comprising a block tip with an elongated face and a row of jet orifices in said face for directing scarffing streams of oxygen against the surface of a metal body, and supporting bearings on a side of the block at spaced regions along the length of the block for supporting the tip on the metal body in a definite relation to the surface of said metal body.

9. A scarffing torch comprising a block tip with an elongated face and a row of jet orifices in said face for directing scarffing streams of oxygen against the surface of a metal body, a supporting bearing on the side of the torch, and air passages in the supporting bearing extending in a direction to supply air to the region under the face of the tip when said tip is in working relation to the metal body to be scarfed and the supporting bearing is resting on the surface of said metal body.

10. A scarffing torch comprising an elongated block tip with a face and a row of scarffing jet orifices opening through the face at spaced regions along the length of the face, a bearing surface on the side of the tip at an angle to the plane of the tip face, said angle being the supplement of the angle that the plane of the tip face makes with the surface of a metal body when the tip is in operating position on said metal body, and parallel grooves in the bearing surface extending across said surface to the edge of the bearing nearest the face of the tip.

11. A scarffing torch comprising a block tip having an elongated face and a bearing on one side by which the torch is supported on the surface of the metal body to be scarfed, jet orifices opening through said face at spaced points along the length of the face for directing scarffing jets of oxygen against the metal body, preheating jet orifices opening through the tip face under the oxygen jet orifices, and air passages through the supporting bearing for the supply of air to the preheating flames under the oxygen jets.

12. Surface conditioning apparatus comprising a head having a front face; a row of gas passages opening through said front face and adapted to discharge gas against a work surface; passage means in said head for supplying gas to said row of gas passages; interconnected passages in said

head for cooling fluid; bearing means on said head for engagement with said work surface to maintain said gas passages in operative relation to the work surface; and a renewable layer of protective material covering said front face substantially completely except where said gas passages open therethrough.

13. Surface conditioning apparatus comprising a head; a row of gas discharging nozzles secured along the front of said head; a shoe secured to said head and adapted substantially to enclose said nozzles except the orifice ends thereof and cooperating with said head to form a chamber for cooling fluid around said nozzles, said shoe having a front face through which said nozzles extend; and a renewable layer of protective ma-

terial covering said front face substantially completely except where said nozzles extend therethrough.

14. Surface conditioning apparatus comprising a head; a row of gas discharging nozzles secured along the front of said head; a unitary shoe secured to said head and forming a closed cooling fluid chamber with the front of said head, said shoe having a front wall with openings into which said nozzles extend, said nozzles extending through said chamber and preventing loss of cooling fluid through said openings; and passages in said head for cooling fluid opening into said chamber for passing the cooling fluid into and out of said chamber.

JAMES H. BUCKNAM.
